(57) **CLAIM**

The ornamental design for a brush handle, as shown and described.

DESCRIPTION

FIG. 1 is a perspective view of one embodiment of a brush handle showing my new design;

FIG. 2 is a side elevation view thereof;

FIG. 3 is a front elevation view thereof, the rear elevation view being identical;

FIG. 4 is a top plan view thereof;

FIG. 5 is an enlarged side elevation view taken along circle 5 in FIG. 3;

FIG. 6 is an enlarged sectional view taken along line 6-6 in FIG. 5;

FIG. 7 is an enlarged sectional view taken along line 7-7 in FIG. 5;

FIG. 8 is a perspective view of a second embodiment of a brush handle showing my new design;

FIG. 9 is a side elevation view thereof;

FIG. 10 is a front elevation view thereof, the rear elevation view being identical;

FIG. 11 is a top plan view thereof;

FIG. 12 is an enlarged front elevation view taken along circle 17 in FIG. 15;

FIG. 13 is an enlarged sectional view taken along line 18-18 in FIG. 17; and,

FIG. 14 is an enlarged sectional view taken along line 19-19 in FIG. 17.

The broken lines illustrate the bounds of the claim as well as the bounds of the enlarged views, and indicate where in the original drawing the enlarged views were taken. None of the broken line subject matter forms part of the claimed design. Further, the broken away symbols (the brackets) in the drawings indicate that any portion of the article beyond what is shown forms no part of the claimed design.
